UNITED STATES PATENT OFFICE.

SAMUEL NAISMITH, OF CHICAGO, ILLINOIS.

BASIC OPEN-HEARTH FURNACE.

1,220,444.

Specification of Letters Patent. Patented Mar. 27, 1917.

Application filed April 17, 1916. Serial No. 91,603.

To all whom it may concern:

Be it known that I, SAMUEL NAISMITH, a citizen of the United States, residing at Chicago, in the county of Cook and State 5 of Illinois, have invented new and useful Improvements in Basic Open-Hearth Furnaces, of which the following is a specification.

My invention relates more particularly to 10 basic open hearth and reheating furnaces used for metallurgical purposes and has for its object a new and useful improvement for the preservation of the slag-line and means for supporting the furnace walls adjacent thereto. It is a further object of my 15 invention to provide an improved means to prevent the basic and acid linings of the furnace from fluxing or uniting.

Basic open hearth furnaces used for 20 metallurgical purposes are gas furnaces adapted for manufacturing steel, in which the hearth is usually made up of a layer of second grade brick, a layer of first grade brick, a layer of magnesite brick, provided 25 with a substantial lining of basic material, either magnesite or burnt dolomite, the side walls and roof of the furnace being constructed of acid material, usually silica brick. At the joint where the hearth joins 30 the remainder of the furnace there is placed between the two materials, to retard their fluxing, a neutral joint of passive material, usually chromite. That part of the furnace at and near the neutral 35 joint is known as the slag-line; the interior of the furnace at the slag-line is provided with a bank of magnesite or the like, for the purpose of combating the attack of the slag on the walls of the hearth.

40 The slag, which is usually a few inches in depth, is composed of the impurities in the metal, scrap iron, etc., caused by oxidation, and always contains magnesia, which makes it very pernicious and extremely destructive to the walls of the hearth at the slag-line, and when high in silica, as is frequently the case, it attacks the hearth and banks and undermines the walls of the furnace, causing them to collapse. This often 45 occurs while the heat of steel is in the furnace. It then becomes necessary to shut off the gas while the walls are being replaced and in the meantime the heat of steel becomes chilled and must be again melted, thus resulting in considerable delay and expense.

The slag-line, which as before stated, is that part of the furnace at and near the point where the hearth joins the remainder of the furnace, is composed of grain magnesite and magnesite brick, which, at best, are unsatisfactory and expensive, for which such a construction the slag line must be banked, repaired or fettled after every heat, which is every nine and one-half 60 (9½) hours, with burnt dolomite, grain magnesite or some other basic refractory material, and set at a high temperature before the furnace is again in condition to receive the next charge. This method is expensive 65 and results in considerable delay. With my invention the necessity of banking or repairing after every heat is eliminated, as I place a water cooler or series of water coolers in the wall of the furnace at the 70 slag-line, adjacent to the banks of basic material, as a result of which the walls and basic material at or near this point are kept cool and in such condition as to withstand the pernicious attack and wash of the 75 slag, and the walls from being eaten out or undermined.

In basic open hearth furnaces the hearth, as before stated, is lined and banked with basic material, while the side walls and 80 roof of the furnace are constructed of acid material, usually silica brick. With the intense heat within such a furnace, particularly when charged with a spray of iron oxid, the acid and basic materials will flux 85 or unite, and, in fact, when the silica brick melts, the acid runs down and cuts out the basic material pretty much as hot water would snow. With a view of eliminating this in the present constructions, there is 90 utilized a neutral joint at the slag-line of chromite or other passive material, between the silica brick walls, the basic banks and walls of the hearth, but this method is unsatisfactory and expensive. With my invention 95 the chromite joint is eliminated entirely, as the water cooler serves as a joint in place of the chromite and keeps the basic and acid materials cool and prevents any fluxing or the melting of the silica brick, 100 and the acid from the brick running down into the basic material.

In the construction disclosed in the accompanying drawings, the weight of the silica walls and roof are carried on buck 105 stays, the roof channel being suspended from the top of the buck stays and the side

walls being supported by an angle iron which is securely bolted to the buck stays immediately above the water coolers. This construction relieves the basic bottom or hearth of all weight and by placing the water coolers immediately below and adjacent to the supporting means of the wall and above the walls of the hearth the two materials are prevented from disintegration, and the supporting means for the silica walls kept cool and protected.

The water coolers are readily detachable, so that in the event any of them should happen to give way they can be readily and quickly removed and replaced without the necessity of shutting off the gas or allowing the heated steel to become chilled.

The above and other features of novelty, advantages and capabilities will become apparent from the detail description of the accompanying drawings, in which I have illustrated a practical embodiment of the invention, but the construction there shown is to be understood as illustrative only, and not as defining the limits of the invention.

Figure 1 is an elevation showing a part of the front of a furnace embodying one form of my invention.

Fig. 2 is an elevation of a portion of the back wall.

Fig. 3 is a vertical sectional view of such furnace.

Fig. 4 is a longitudinal view in horizontal section of the same, and

Fig. 5 is a detail perspective view of one of the water coolers apart from the furnace, showing the connections therewith.

Referring to the drawings in detail, the air ports are shown at 10 and the gas ports at 11, which are typical of a furnace of this type. The hearth 12, which is of the usual form of construction, is supported on a suitable frame as shown and comprises a layer of second grade brick 13, a layer of first grade brick 14, a layer of magnesite brick 15, which is extremely expensive as it is imported from Austria, and which, at the present time, is difficult to obtain owing to the fact that the supply in this country is about exhausted. The layer of magnesite brick 15 is provided with a substantial lining of grain magnesite or dolomite 16. The hearth at one of its lower sides is provided with the usual tapping opening 17 for discharging the steel after it has been properly treated. This opening, of course, has the usual closure. The entire furnace is bound together at the sides and ends by a series of buck stays 18, which are connected together at their tops by means of rods 19 and at their lower edges by the cross-beams 20. Spaced above the upper edge of the walls of the hearth 12 at the front, sides and back of the furnace is an angle iron 21, (best shown in Fig. 3) rigidly secured to

the buck stays 18 by any suitable means, such as the bolts shown. Constructed on and supported by these angle irons 21 are the side walls 22 of the furnace, which are made of silica brick. Connecting with the upper edge of the side walls 22 is the arch roof 23, which roof is carried by and supported on the channels 24, which are suspended by means of the rods 25 from the upper channels 26, which latter channels are supported by means of the buck stays 18. Within the space between the upper edge of the walls of the hearth and the lower edge of the side walls 22 is placed a water cooler or series of water coolers 27. These are set in toward the interior of the furnace so as to be adjacent to the lining or banks 28 of the furnace. This is a portion of the furnace which is most severely attacked by the slag by reason of its composition and washing action, and is the point where failure of the furnace usually occurs, and, with the metallurgical furnaces now in use this part becomes damaged and burned out to an appreciable extent during every heat, and for that reason must be repaired or fettled after each heat, which is every nine and one-half (9½) hours, or, as is commonly said, must be banked after every heat, and from this arises the word "banks" as designating that particular part of the furnace. The banks, as before stated, are usually constructed of burnt dolomite, grain magnesite or some other basic refractory material, and set at a high temperature before being in condition to receive the next charge. This method is expensive and results in delay, but with the water coolers of my invention placed adjacent to the banks, the burning out or eating away of them by the slag is greatly reduced and the necessity of repairing, fettling or banking after each heat entirely eliminated. The upper sides of the coolers 27 engage or are adjacent to the silica walls 22 and prevent these walls from melting and running down into the banks or hearth and eating out the basic lining, and also protects the angle irons for supporting the walls 22. At the sides and back of the furnace the water coolers may be one continuous container, but at the front, on account of the plurality of doors, it is desirable that these be constructed of a series of coolers, as best shown in Figs. 2 and 4. A circulation of cool water is going on through all of these coolers while the furnace is in use. The cool water is introduced to the coolers at the bottom thereof by means of the pipes 29, and discharged at the top of the coolers by means of the pipes 30. From this it will be seen that a circulation of cool water may be carried on continuously through the coolers as the result of which the banks 28, side walls 22 and hearth 12 are kept cool, and that all the advantages and features set forth for this

invention, as well as others, are readily accomplished by the use of it.

Moreover, with my invention the layer of magnesite brick 15, forming a part of the hearth, which is very expensive, costing six hundred dollars (\$600.00) a thousand and extremely difficult to obtain at the present time, because of the necessity of importing it from Austria, could be eliminated, as the coolers prevent the intense heat from attacking the brick of the hearth.

By providing separate supporting means for the walls 22 and the roof 23, as above described, the basic hearth is relieved of the weight of the walls and roof and the construction allows for the expansion and contraction of the walls and prevents the breaking or disruption of the walls from such forces.

20 I claim:

1. In a basic open hearth furnace, a cooler positioned to serve as a neutral joint between the acid brick and basic lining to prevent fluxing.
2. In a furnace of the class described, a series of readily removable water coolers positioned in the walls of the furnace at the slag line and near the lining thereof, and means for producing a circulation of water 30 through said coolers.
3. In a furnace of the class described, a series of buck stays adjacent to the outer surface of the furnace, and means secured directly to the buck stays for supporting the wall of the furnace to relieve the hearth of the weight thereof.
4. In a furnace of the class described, a series of buck stays adjacent to the outer

surface of the furnace, an angle iron secured directly to the buck stays for supporting the wall of the furnace.

5. In a basic open hearth furnace, a cooler at the slag line and adjacent to the banks for the purpose set forth.

6. In a basic open hearth furnace having a hearth and vertical walls, means for supporting the vertical walls independently of the hearth and a cooler adjacent to the supporting means for protecting the same.

7. In a furnace, a series of buck stays extending above the furnace, means connected directly with the back stays for supporting the vertical walls independently of the hearth and means connecting with the buck stays for suspending the roof therefrom and supporting it independently of the vertical walls.

8. In the combination of a furnace provided with basic and acid linings, and water cooler positioned between said linings to prevent their fluxing.

9. In a furnace, a series of buck stays extending above the furnace, an angle iron connected directly with the buck stays for supporting the vertical walls, channel irons suspended from and connected with the upper ends of the buck stays for supporting the roof.

In witness whereof, I hereunto subscribe my name to this specification in the presence of two witnesses.

SAMUEL NAISMITH.
